COLLAPSIBLE TUBE SQUEEZING DEVICE

Fred E. Holt, Santa Monica, Calif.

Application August 27, 1948, Serial No. 46,531

7 Claims. (Cl. 222—102)

1

This invention relates to a collapsible tube squeezing device for dispensing a paste or cream such as tooth paste, shaving and facial creams and like materials.

One of the objects of the present invention is to provide a dispensing device in which a collapsible tube may be readily placed and so constructed that the collapsed tube section during dispensing will at all times be out of sight. A further object of the invention resides in the provision of three rollers for squeezing the tube and means for manually rotating one of the rollers. A still further object resides in a squeezing device for collapsible tubes in which a wide flexible band or belt preferably of rubber, is provided to increase the longitudinal squeezing surface from a line of contact to a curved surface of contact. Thus another object of the invention resides in the provision of two spaced rollers provided with the flexible band and a third roller normally bearing against and contacting one of the runs of the belt between which run and belt the collapsing and collapsed tube passes to thereby provide an area squeezing contact instead of an approximate line contact.

Another object of the invention resides in the arrangement of the squeezing elements to eliminate swaying of the tube and lateral tracking for the tube by providing a belt or band guide and conveyor for the collapsing tube.

A still further object of the invention resides in the structure of the tube squeezing device in which the frame is made in one or two parts for easy assembly of the squeezing rolls and associated parts and when made in one part it may be joined at the bottom.

Further objects will be apparent from the following description when considered in connection with the accompanying drawings in which:

Figure 1 is a front elevation of the tube squeezing device with tube inserted, and showing certain parts broken away and in section.

Figure 2 is a longitudinal section taken on line 2—2 of Figure 1.

Figure 3 is a cross-section taken on line 3—3 in the direction of the arrows.

Figure 4 is a perspective view of the detail of a cover.

Figure 5 is a perspective view of the upper part of the device showing various details, and

Figure 6 is a cross section taken on line 6—6 of Fig. 1.

The base or frame 14 may be made integral

2

by joining the parts 1, 2, and 3 at the sides. A perforation 15 is provided which forms a means for suspending or mounting the device on a vertical surface. Each part 1, 2, and 3 appears in cross section as best shown in Figure 3 which shows a main side section 16 and a transverse or back section 17 with a meeting edge 31. Each side section 16 is provided with an inner surface or channel 18 defined by the section 16 and a projecting lip or ridge 19.

A closure plate or disc 12 is slidably arranged in the channels or grooves 18 and this plate is provided with side arms 20 each bent at approximately right angles relative to the plate to contact its channel 18 to thereby frictionally maintain the plate in any position as for instance against the opening or port 21 of the tube 22, Figure 2, to act as a closure.

The upper part of frame 14 is provided with numerous holes acting as bearings for a plurality of rollers 4, 11, and 6. Roller 4 is a driving roller and roller 6 is a driven roller, the driving thereof being affected by a flexible belt or band 10 preferably made of rubber and preferably integral and extending in width the entire length of the rollers 4 and 6. The roller 11 acts as a contact or base roller on which the collapsible tube 22 rolls in contact with and as driven or squeezed by the band 10 as best seen in Figure 2. The roller 11 is preferably provided with a gear 5 which meshes with a similar gear 8 secured to the roller 4. A driving shaft 9 is rotatably mounted in the upper part of the frame 14 and is provided with a gear 7 and with a manual actuating wheel or knob 24 of which two are preferably provided one on each end of the shaft 9, as best seen in Figure 1.

It will be seen in Figure 5 that the frame 14 is provided along each upper part or side section 16 with a stepped or recessed portion 25 extending U-shaped around the top of each side section. Also each leg of the U is provided with projecting lugs or tongues 26 which cooperate with notches or detents 27 provided in a cover member 13. This cover 13 also made of metal or plastic or any other suitable substance is U-shaped and is provided with an internal peripheral rim 28 in which the detents 27 are provided as best seen in Figure 4. The cover 13 has a plurality of functions as for instance to act as a cover for the moving parts of the squeezing mechanism and to maintain the rollers in their bearings. Also the cover 13 acts to maintain the upper parts 1, 2, and 3 of the frame together and as a means by which a holding clip 29, Figure 2, may grip

the device for support on a vertical surface.

Fig. 5 shows the sections 16 separated somewhat to illustrate how the rollers, band and drive shaft may be inserted in their respective holes in the sections driving the assembly of the device.

As clearly shown in Figure 6 the frame 14 may be composed of two sections of parts pivotally held together by means of the screw 33.

The operation of the device is as follows.

To insert a full collapsible tube it is merely necessary to slide the closure 12 down to the dotted line position 30, Figures 1 and 2, and then insert the flat end 34 of the collapsible tube 22 between the roller 11 and the flexible band 18. Then upon rotation of the actuating wheels 24 the shaft 9 rotates the gear 7 which in turn rotates the gears 8 and 5 as a gear train and as a result thereof the roller 4 will be driven clockwise, Figure 2, and the roller 11 counterclockwise. Thus the tube 22 will be squeezed between the roller 11 and belt 10 to dispense the material from the tube through the port 21. After the dispensing operation the closure 12 is moved upwardly in its channels 18 to close the port.

The spent or collapsed tube passes down behind the back sections 17 so that it will be out of sight, assuming that the device is mounted on a vertical surface as shown in Figure 2. When the tube is completely emptied and almost completely behind the back sections 17, the hand wheels 24 may be moved in reverse rotation to roll the empty tube out of the device preparatory to the insertion of a new tube.

The device is easily installed by simply securing the bracket 29 on the surface where the device is to be mounted, by means of a screw 32, then slide the device down until the cover 13 hooks over and behind the bracket 29 and then insert the screw 33 through the perforation 15.

From the foregoing it will be evident that in view of the area contact of the roller 11 and band 10 the tendency to slip and sway is entirely eliminated. The rubber band 10 acts as a guide and conveyor and thus by having a large area of contact, both longitudinally as well as laterally, instead of only a lateral line contact, the tube will be forced in a straight direction and without any slippage and side sway.

I claim as my invention:

1. A squeezing device for collapsible tubes and the like comprising an elongated base frame, means at one end for collapsing the tube, and a closure plate slidably mounted in the frame to act as a direct closure for the tube, said means including a roller around which the tube collapses and a band to press the collapsing tube on the roller, and a pair of spaced rollers rotatably mounted in the frame to support and actuate the band.

2. A squeezing device for collapsible tubes and the like comprising an elongated base frame, means at one end for collapsing the tube, and a closure plate slidably mounted in the frame to act as a direct closure for the tube, said means including a roller around which the tube collapses and a band to press the collapsing tube

on the roller, and said band and roller presenting a wide area both longitudinally and laterally to the tube to prevent slippage and lateral sway, and a pair of spaced rollers rotatably mounted in the frame to support and actuate the band.

3. A squeezing device for collapsible tubes and the like comprising an elongated base frame, means at one end for collapsing the tube, and a closure plate slidably mounted in the frame to act as a direct closure for the tube, said means including a pair of spaced rollers, a flexible band driven by said rollers and a base roller around which the tube is flattened by the band.

4. A squeezing device for collapsible tubes and the like comprising a base frame having a rear section and side sections and means at one end of the frame to squeeze and collapse the tube, the collapsed tube passing from the squeezing means and behind the rear section out of view, and a closure plate frictionally slidable in and between the side sections.

5. A squeezing device for collapsible tubes and the like comprising a base frame having a rear section and side sections and means at one end of the frame to squeeze and collapse the tube, the collapsed tube passing from the squeezing means and behind the rear section out of view, said squeezing means including a roller and a belt between which the tube is collapsed with a wide contact area to prevent slippage and lateral sway of the tube.

6. A squeezing device for collapsible tubes and the like comprising an elongated base frame joined at one end to form a U-shaped member with two parts at the other end of the frame, a plurality of spaced rollers rotatably mounted at the other end of the frame and a band cooperating with the rollers to squeeze the tube, and a cover for the said two parts of the frame to conceal the rollers and band and to hold the two parts of the frame together.

7. A squeezing device according to claim 6, in which a closure plate is provided slidable by frictional engagement in the two parts of the frame to act as a closure for the tube.
